UNITED STATES PATENT OFFICE.

WALTER WILLIAM PHILLIPS, OF SWANSEA, ENGLAND:

DESIGN FOR A TIP FOR BOOTS OR SHOES.

SPECIFICATION forming part of Design No. 29,950, dated January 3, 1899.

Application filed May 26, 1898. Serial No. 681,843. Term of patent 14 years.

to all whom it may concern:

Be it known that I, WALTER WILLIAM PHILLIPS, a subject of the Queen of England, residing at Swansea, county of Glamorgan, England, have invented and produced a new and original Design for Tips for Boots or Shoes, which the following is a specification.

The object of this invention is to provide for the heels of boots and shoes a durable tip which shall cause the heel to be more comfortable and less noisy than the heel as usually worn and which can be easily applied.

The accompanying drawing illustrates by a perspective view a tip for boots and shoes, showing my new design.

The tip A, of india-rubber or similar sub-

stance, is made thick and has a rectilinear inner side D and a curved outer side C, corresponding with the shape of the heel to which it is to be fixed.

The tip is provided with a row of nail-receiving holes B, arranged along the inner edge of the tip, as shown.

What I claim as new, and desire to secure by Letters Patent, is—

The design for a boot and shoe tip, as herein shown and described.

WALTER WILLIAM PHILLIPS.

In presence of—

PHILIP L. PRICE,

JNO. HENRY HARRIS.
